UNITED STATES PATENT OFFICE.

WILLIAM A. MOORE, OF BROOKLYN, NEW YORK.

TELEPHONE-SWITCH.

SPECIFICATION forming part of Letters Patent No. 556,763, dated March 24, 1896.

Application filed September 5, 1895. Serial No. 561,497. (No model.)

To all whom it may concern:

Be it known that I, WILLIAM A. MOORE, a citizen of the United States of America, and a resident of Brooklyn, Kings county, New York, have invented a new and useful Improvement in Telephone-Switches, of which the following is a specification, reference being had to the accompanying drawings, forming part of the same, in which—

10. Figure 1 shows a horizontal section of a transmitter-case, an upper face view of a switch embodying my invention, and an elevation of a receiver suspended from the hook of the switch, the parts being shown in the position which they occupy when the battery is cut out. Fig. 2 is a view of substantially similar parts in the positions they occupy when the battery is cut in. Fig. 3 is a plan view of some of the parts shown in Fig. 1, 15 the spring-contacts being removed and the underlying parts shown in dotted lines. Fig. 4 is an under face view of the switch in the position shown in Fig. 1, and Fig. 5 is a central vertical sectional view of a portion of 20 the transmitter-case and the switch contained therein.

25. My invention relates to telephone-switches, and especially to that class in which some member of the device is used as a supporting-hook for one of the telephonic instruments.

The end most sought after in telephone-switches is some arrangement that will prevent the leaving of the instruments in the place they are intended to occupy when not in use without first cutting out the battery-circuit, so that there shall be no waste of power. This has been accomplished by what is known as the "gravity-switch," but my aim has been to accomplish it by what I may term 30 a "positive" movement, not controlled by or dependent upon gravity or its equivalents, and at the same time to arrange the parts so that they may be in small compass to accommodate their placing in the case of the transmitter, if desired, where I prefer to place them, and I also prefer to suspend the receiver from some member of the switch, as that is the more convenient arrangement.

In the drawings, C represents the transmitter-case. Its special form or arrangement 35 is not material. Within it I arrange a switch-board B, secured in any suitable manner—

here by screws s, passing into lugs in the case. Pivoted on this switchboard or some suitable support is a finger lever or switch F, and adjacent to its path are contact-points p p' p², of which I show three, though more or less may be used dependent upon the wiring.

We will suppose, for example, the battery-circuit is through contact p, the lever F and contact p', when they are in the position shown in Fig. 2. In a suitable bearing, as b, I support a hook H, arranged to slide in and out, and when in to have its hook substantially closed by the abutting of the point 55 against the bearing b or some adjacent part. At or near the inner end I provide hook H with two fingers f, arranged preferably at right angles to the line of movement of the main shaft of the hook. On the under face 60 of the switchboard I pivot a lever L, preferably in elbow form, and secured to it I arrange a pin p³, so placed that it will reach down and stand between the fingers f. Another pin, p⁴, extends down from switch-lever 65 F through slot s' in the board B and into slot s² in the lever L. There is also a slot S in the case inclosing the switch, through which the lever F extends and in which it may work.

The operation of the device is manifest. 70 When the device is not in use the receiver hangs on the hook, as seen in Fig. 1, and the battery is cut out, the circuit being broken from point p to p', they being insulated one from the other in any suitable way, here by 75 having the board B of insulating material. Now one wanting to use the telephone seizes the receiver and removes it from the hook and then swings the lever F to the left, thereby closing the circuit from contact p to contact 80 p' and cutting in the battery; but when this is done the pin p⁴, connected to the lever F and passing into slot s', carries that end of lever L to the left and necessarily swings the other end and its connected pin p³ inward. 85 The pin p³, pressing upon the inner of fingers f, draws the hook H inward till the point rests upon the abutment of bearing b. The operator finishes his communication and then desires to hang up the receiver, but this he can 90 not do until he forces out the hook H by reversing the movement above described by swinging the lever F to the right, when he of course breaks the battery-circuit and the re- 95 100

sult is that the battery will not be left in circuit through the carelessness or forgetfulness of the operator, the end to be attained. At the same time the switch is compact and takes up little space in the transmitter-case, where it is usually desired, it is positive, does not depend upon gravity or springs, is not likely to get out of order and is inexpensive.

The fingers *f* constitute a slot or hinge and a flat slotted piece could be readily substituted therefor.

What I claim as my invention, and desire to secure by Letters Patent, is—

1. A switch composed of a finger-lever, combined with a hook supported in a bearing, an intermediate pivoted lever provided with a pin and a slot, the pin arranged to engage pins connected to the hook and the slot engaged by a pin connected with the finger-lever together with one or more contact-points arranged as described whereby when the finger-piece is in one position the circuit from one point to the other is broken and the hook is projected and vice versa, all substantially as set forth.

2. The combination with a transmitter-case, of a finger-lever extending through a slot in said case, a hook supported in a bearing and extended through said case, an intermediate pivoted lever provided with a pin and a slot, the pin arranged to engage pins connected to the hook and the slot engaged by a pin connected with the finger-lever, together with one or more contact-points arranged as described, whereby when the finger-piece is in one position the circuit from one point to the other is broken and the hook is projected and vice versa, all substantially as set forth.

3. The combination with a case, of a finger-piece extending through a slot in said case and pivoted on a switchboard of insulating material secured therein, a hook supported

in a bearing and extending through said case on the side of the board opposite to that on which the finger-piece is pivoted, an intermediate elbow-lever pivoted to said board and provided with a downwardly-extending pin and a horizontal slot, the pin arranged to engage pins connected to the hook and the slot engaged by a pin connected with the finger-lever, together with one or more contact-points arranged as described, whereby when the finger-piece is in one position the circuit from one point to the other is broken and the hook is projected and vice versa, all substantially as set forth.

4. The combination in a telephone-switch of a finger-lever, one or more contact-points, a sliding hook and positive continuous connections between the finger-lever and the sliding hook, substantially as set forth, whereby, without other force, the movement of the finger in one direction will break contact and extend the hook and the movement of said finger-lever in the opposite direction will make contact and retract the hook, all substantially as set forth.

5. The combination in a telephone-switch of one or more contact-points, a finger-lever, a sliding hook, an elbow-lever interposed between the finger-lever and the sliding hook, and positive continuous connections from said finger-lever to the elbow-lever and from the elbow-lever to the sliding hook, all arranged and combined to operate, substantially as set forth.

In testimony that I claim the foregoing as my invention I have signed my name, in presence of two witnesses, this 13th day of August, 1895.

WILLIAM A. MOORE.
